UNITED STATES PATENT OFFICE.

MILTON B. ROLLER, OF SAN FRANCISCO, CALIFORNIA.

DESIGN FOR AN ANDIRON.

56,539.

Specification for Design.

Patented Nov. 2, 1920.

Application filed April 19, 1919. Serial No. 291,390. Term of patent 7 years.

To all whom it may concern:

Be it known that I, MILTON B. ROLLER, a citizen of the United States, residing at San Francisco, in the county of San Francisco and State of California, have invented a new, original, and ornamental Design for an Andiron, of which the following is a specification, reference being had to the accompanying drawing, forming part thereof.

Figure 1 is a perspective view of an andiron, showing my new design.

Fig. 2 is a vertical central section through the same.

I claim:

The ornamental design for an andiron, as shown.

MILTON B. ROLLER.
